(57) **CLAIM**

The ornamental design for a frame for basin, as shown and described.

DESCRIPTION

FIG. 1 is a top plan view of a frame for a basin, showing my new design in an unfolded configuration of use;

FIG. 2 is a rear view thereof;

FIG. 3 is a perspective view thereof;

FIG. 4 is a bottom view thereof;

FIG. 5 is a right side view thereof;

FIG. 6 is another perspective view thereof, but shown in folded configuration;

FIG. 7 is a front view of FIG. 1; and,

FIG. 8 is a left side view thereof.

The broken lines illustrate portions of the frame for basin that forms no part of the claimed design.

1 Claim, 8 Drawing Sheets
